UNITED STATES PATENT OFFICE.

CHARLES H. WARNER, JR., OF ST. LOUIS, MISSOURI, ASSIGNOR TO THE
GREAT WESTERN GLASS WORKS, OF SAME PLACE.

DESIGN FOR A GLASS FLASK.

SPECIFICATION forming part of Design No. 13,526, dated January 16, 1863
Application filed November 17, 1862. Term of patent 7 years.

To all whom it may concern:

Be it known that I, CHARLES H. WARNER, Jr., of St. Louis, Missouri, have invented a certain new Design for Glass Flasks, of which 5 the following is a specification, reference being had to the accompanying drawings, forming part of the same.

Figure 1 is a view of the flask, one-half in front elevation and one-half in vertical section at 1.1. Fig. 2 is one-half in side elevation and one-half in section at 2.2.

The peculiar character of this flask is a general rounded appearance, there being no sharp lines or corners in any part of the flask.

15 A is the body of the flask, and B the neck. The transition C between the body and the neck is very gradual, there being an absence

of the abrupt curves found at this point in glass flasks as heretofore constructed. The shoulders D have an easy curve fading into 20 the curve of the side of the neck above and into the side of the body below. There is a recess, E, at the bottom of the flask, having rounded corner F all around, that forms the foot of the flask at its lower part, and which 25 fades into the sides above, so that there is no sudden curve or corner at the bottom.

I claim as my invention—

The design for a glass flask formed substantially as shown and described.

CHARLES H. WARNER, JR.
